Primary Examiner — George A Bugg*Assistant Examiner* — Tamara L Hahn(74) *Attorney, Agent, or Firm* — Foley & Lardner LLP(57) **CLAIM**

The ornamental design for a pallet rail, as shown and described.

DESCRIPTION

FIG. 1 is a front perspective view of a first embodiment of a pallet rail;

FIG. 2 is a front view of the pallet rail, the rear elevation view being a mirror image thereof;

FIG. 3 is a right side view of the pallet rail, the left side view being a mirror image thereof;

FIG. 4 is a top view of the pallet rail;

FIG. 5 is a bottom view of the pallet rail;

FIG. 6 is a front perspective view of a second embodiment of a pallet rail;

FIG. 7 is a front view of the pallet rail, the rear elevation view being a mirror image thereof;

FIG. 8 is a right side view of the pallet rail, the left side view being a mirror image thereof;

FIG. 9 is a top view of the pallet rail; and,

FIG. 10 is a bottom view of the pallet rail.

The broken lines in FIGS. 1 through 10 depict portions of the pallet rail that form no part of the claimed design.

1 Claim, 6 Drawing Sheets(56)
